UNITED STATES PATENT OFFICE.

GEORGE GUILD, OF CAMBRIDGE CITY, INDIANA, ASSIGNOR TO BERTSCH & CO., OF SAME PLACE.

BENDING-MACHINE.

SPECIFICATION forming part of Letters Patent No. 610,585, dated September 13, 1898.

Application filed December 4, 1897. Serial No. 660,755. (No model.)

To all whom it may concern:

Be it known that I, GEORGE GUILD, of Cambridge City, Wayne county, Indiana, have invented certain new and useful Improvements 5 in Bending-Machines, of which the following is a specification.

This invention pertains to improvements in machines for bending sheet metal in forming boxes, pans, moldings, &c., and the improvements will be readily understood from the following description, taken in connection with the accompanying drawings, in which—

Figure 1 is a front elevation of a machine embodying my improvements; Fig. 2, a plan of the same; Fig. 3, a side elevation, and Fig. 4 a vertical transverse section of the dies and their holders.

In the drawings, 1 indicates a sole-plate; 2, a head-plate; 3, four columns uniting the sole-plate and head-plate and with them forming the frame or body of the machine; 4, a die-carrier having ears engaging the columns 3, so as to slide thereon to and from the head-plate; 5, a pair of hydraulic cylinders vertically disposed 25 on the sole-plate, one between each pair of columns and under the ends of the die-carrier 4; 6, a pipe for supplying these cylinders with liquid under pressure; 7, the rams of the cylinders, extending upwardly from the cylinders 30 into rigid attachment with the under surface of the die-carrier; 8, a pair of studs having enlarged bases secured removably at the ends of the die-carrier and projecting upwardly therefrom between the columns; 9, vertical screws 35 threaded into nuts on the head-plate, these screws being disposed vertically over the studs 8; 10, a worm-wheel splined on each of the screws 9; 11, a handled worm-shaft mounted in bearings on the head-plate and serving 40 to give simultaneous rotary motion to the two worm-wheels 10, whereby the turning of the shaft serves in vertically adjusting the lower ends of screws 9; 12, the lower die-holder or die-holders in the form of a sectional plate 45 resting edgewise on the die-carrier 4, to which it is firmly secured by bolts through a flange in its base, the upper edge of the die-holder 12 being provided with an upwardly open groove; 13, the lower dies in the form of plates 50 with their lower edges seated in the groove in the top of die-holder 12, the upper edge of

these dies having a cross-sectional form suited to the form of bend to be produced, the exemplification showing these dies as having angular edges suited for square or bevel bends; 55 14, an upper die secured to the lower surface of the head-plate and having along its lower surface a die-groove forming a counter-die corresponding with the upper edge of dies 13; 15, sectional upper dies in the form of blocks 60 removably secured to and projecting downward from die 14, these sectional upper dies having in their lower surfaces counter-grooves to coöperate with lower dies 13; 16, guide-brackets on the lower surface of the head-plate to the rear of die 14; 17, carriages sliding on these guide-brackets; 18, a gage-plate secured to these carriages and presenting its forward face parallel with the dies and extending somewhat below the upper dies; 19, 70 screws journaled in guide-brackets 16 and threaded into the carriages 17; 20, worm-wheels on these screws, and 21 a handled worm-shaft for operating screws 19 simultaneously, whereby gage 18 may be adjusted to 75 and from the upper dies.

By properly admitting liquid to the two cylinders 5 it is obvious that die-carrier 4 and the dies carried by it will be pressed upwardly to the upper dies, this upward motion being limited by studs 8 coming in contact with screws 9, which screws may be adjusted by means of shaft 11, so that the lower dies will enter more or less into the upper dies. 85

In cases where a sheet is to have only one bend or several parallel bends a lower die may be employed having any length within the capacity of the machine, and such die may coöperate directly with long upper die 90 14; but where a sheet is to be bent and then have additional bends at right angles to the first bend—as, for instance, in turning up the sides of a square pan or box—then the long lower die may not answer, and in such 95 case the lower dies 13 are to have a length corresponding with the inside dimensions of such box or pan. Dies 13 of different lengths may be provided, and it is to be noticed that die-holder 12 is deeply notched to permit of 100 the presence of those edges of the sheet metal formed by the first bendings and standing at

right angles to the line of the bending to be done. The notches in die-holder 12 may obviously be notches in the integrally-formed die-holder or they may be formed by the separations between the sections of the die-holder if made in separate sections, and Fig. 1 may be taken as illustrating die-holder 12 as being formed in one or more pieces.

In some cases there may be reverse bends wanted, in which case the long upper die will not be satisfactory, and it also, like the lower die, will require to be notched or have special lengths. In the illustration the sectional upper dies 15 provide an upper die of definite short lengths with intervening notches.

The machine may thus be employed with a single pair of dies or a single pair of short dies or with a multiplicity of pairs of short dies of varying length, and the dies are readily changed.

In using the machine the back gage 18 is properly adjusted, and then the sheet is held up against the upper die, its rear edge coming against the gage, after which the lower die is moved upwardly to do the bending.

I claim as my invention—

1. In a bending-machine, the combination, substantially as set forth, of a sole-plate, a head-plate, rigid connections between these parts, a cylinder secured at each end of the sole-plate and projecting toward the head-plate, a ram projecting upwardly from each cylinder, a die-carrier having its opposite ends secured to the respective rams, a pipe connecting both cylinders with a source of pressure-supply, and suitable dies carried by the head-plate and die-carrier.

2. In a bending-machine, the combination, substantially as set forth, of a sole-plate, a head-plate, two pairs of columns rigidly connecting the sole-plate to the head-plate, a cylinder secured at each end of the sole-plate between the two columns of the pair and projecting toward the head-plate, a pipe connecting both cylinders with a source of pressure-supply a ram projecting upwardly from each cylinder, a die-carrier having its ends secured to said rams and having sliding engagement with said columns, and dies removably secured to the undersurface of the head-plate and to the upper surface of the die-carrier.

3. In a bending-machine, the combination, substantially as set forth, of a head-plate, a

die mounted thereon, a die-carrier arranged to move to and from the head-plate, a die carried by the die-carrier, means for forcibly moving the die-carrier toward the head-plate, studs projecting from the die-carrier toward the head-plate, stop-screws mounted in the head-plate in position to have their ends engaged by the ends of said studs, and arrest the advance of the studs and means for turning said stop-screws simultaneously.

4. In a bending-machine, the combination, substantially as set forth, of a head-plate, a sole-plate, rigid connections between the sole-plate and the head-plate, a die-carrier arranged to move toward and from the head-plate, means for forcibly moving said die-carrier, a die supported by the head-plate, a die supported by the die-carrier, a gage-plate arranged for sliding motion on the head-plate at the rear of and parallel with the die supported by the head-plate, screws supported by the head-plate near each end of the gage-plate, and means for turning said screws simultaneously.

5. In a bending-machine, the combination, substantially as set forth, of a longitudinal die formed of sections separated by intervening notches, extending through the die and a counter-die coöperating therewith.

6. In a bending-machine, the combination, substantially as set forth, of a longitudinal die-holder provided with notches, sectional dies removably secured in said die-holder and separated from each other at the notches of the die-holder, and a counter-die coöperating with said dies.

7. In a bending-machine, the combination, substantially as set forth, of a longitudinal die formed of sections with intervening notches, and a counter-die formed of corresponding sections and with corresponding intervening notches.

8. In a bending-machine, the combination, substantially as set forth, of a longitudinal die formed of sections with intervening notches, a long counter-die adapted to coöperate therewith, and sectional counter-dies removably secured to said counter-die and having spaces between them.

GEORGE GUILD.
